AMANDUS H. CRUSE, OF BROOKLYN, NEW YORK, ASSIGNOR TO R. HOE AND CO., OF NEW YORK, N. Y., A CORPORATION OF NEW YORK.

STEREOTYPE-PLATE-CASTING BOX.

1,206,209.

Specification of Letters Patent. Patented Nov. 28, 1916.

Application filed March 18, 1915. Serial No. 15,277.

To all whom it may concern:

Be it known that I, AMANDUS H. CRUSE, a citizen of the United States, residing at Brooklyn, county of Kings, and State of New York, have invented certain new and useful Improvements in Stereotype-Plate-Casting Boxes, fully described and represented in the following specification and the accompanying drawings, forming a part of 10 the same.

This invention relates to certain improvements in casting boxes, particularly casting boxes for casting the semicylindrical stereotype plates used in rotary printing machines. These plates as now produced are cast from a prepared matrix or mold, this matrix being positioned in the casting apparatus and the metal cast against the matrix. When the matrix is stripped from 15 the casting, the impressions of the matrix are found to be produced in the casting, which then forms the printing plate. In order to produce a plate of such character that the straight edges do not have to be 20 trimmed or finished, it has been customary to use a matrix having an edge or bolster extending along the straight edges by which the matrix is clamped in the mold, this bolster being formed in a plane offset from the 25 type surface of the matrix. When the matrix is in position in the mold, this bolster is offset from the mold body, and unless backed up would be crushed flat by the 30 weight of metal used in making the cast.

It is the object of the present invention to provide an improved backing construction by which a matrix having such offset bolster may be clamped in position and suitably backed up without the necessity of placing 35 the backing in position by hand, the positioning of the side gages also positioning the backing.

For a clear understanding of the invention, reference may be had to the accompanying drawings, in which—

Figure 1 is a perspective view of a portion of a casting box shown partly in section and with certain parts broken away to more clearly show the construction; Fig. 2 50 is a cross section showing a part of the mold with the side gages in open position; Fig. 3 is a similar section showing the side gages partially closed, and Fig. 4 is a similar section showing the side gages in closed position and the matrix backing strip in place.

In the apparatus shown, the invention has been shown as embodied in a hand-operated casting box, though it may be employed in other types of machines if desired.

Referring now to the drawings, 1 indicates a portion of the mold of a hand-operated casting box, the core of the mold having been omitted for the sake of clearness, and 2 indicates the matrix. This matrix is of the type customarily used for producing a 60 plate the straight edges of which do not have to be finished. It is provided for this purpose with a portion 3 along its straight edges offset from the plane of the type surface of the matrix, this offset portion forming what is known as a bolster or clamping edge, this edge, in the particular matrix shown, being a wide edge. This form of matrix, as is well known in the art, produces a plate the straight edges of which do not 65 have to be trimmed.

Casting boxes for casting stereotype plates are provided with side gages 4 which, when in closed position, operate to close the straight sides of the mold, and at the same 70 time to clamp the matrix in position, these side gages determining the thickness of the plate. These side gages extend along the straight sides of the mold and may be positioned in various ways. In apparatus 75 embodying the invention in its best form, for reasons hereinafter appearing, these side gages will be carried in holders 5 which are pivotally mounted on the mold body at 6, in any suitable manner, as for instance by 80 hinges 7, appropriately secured to the mold body.

In machines constructed in accordance with the invention, there will be provided a matrix back which, when in position, will lie 85 between the mold body and the bolster of the matrix, as shown in Fig. 4, so as to back up the matrix and prevent it from being crushed, and acting to clamp the bolster in position against the side gages. This backing is positioned so that it may be moved into position by the closing of the side gages, and in the best constructions, furthermore, this backing will be resiliently 90 mounted so that it will readily position itself 95 between the mold body and the matrix and hold the matrix against the side gage or clamp when the latter is closed. In the particular construction illustrated, this matrix back comprises a bar or strip 8, preferably 100 105 110

having a rounded end 9 so as to more readily position itself. This bar 9 is carried by a plurality of springs 10 secured to the side gage 4 in any suitable manner, as by means 5 of screws 11 passing through the side gage and holding the springs in position.

While but one side of the box has been shown, it will be understood that the construction described will be duplicated on the 10 other side of the box.

As will be apparent from the construction described, the backing being secured to and carried by the swinging side gage, is automatically positioned when the gage is 15 swung to closing position. The end of the side gage as it is swung, as clearly shown in Fig. 3, passes outside the edges of the matrix, and the resiliently mounted back first engages the mold body and slides down on 20 it behind the bolster of the matrix. As it so slides, the side gage comes into the position shown in Fig. 4, and the back forces the matrix against the side gage and effectively clamps it in position. With this construction, therefore, hand positioning of the backing is rendered unnecessary and a matrix 25 can be readily and quickly secured in position and held clamped.

Certain changes and variations may be 30 made in the construction illustrated and described for effecting the purposes of the invention, and it is understood that the invention is not limited to the specific form thus shown and described.

35 What is claimed is:

1. In a casting box, the combination with the mold, of a side gage, and a matrix back movable with the gage and arranged to position itself between the edge of the matrix 40 and the mold and hold the matrix edge out of the plane of the matrix body when the gage is moved to closed position.
2. In a casting box, the combination with the mold, of a side gage, and a resiliently 45 mounted matrix back movable therewith and arranged to position itself between the edge

of the matrix and the mold and hold the edge of the matrix out of the plane of the matrix body when the gage is moved to closed position. 50

3. In a casting box, the combination with the mold, of a pivoted side gage, and a resiliently mounted matrix back carried by the side gage and positioning itself between the edge of the matrix and the mold when the 55 gage is swung to closed position.

4. In a casting box, the combination with the mold, of a side gage, and a spring actuated matrix back carried by the gage and arranged to position itself between the mold 60 body and the edge of the matrix when the gage is moved to closed position.

5. In a casting box, the combination with the mold, of a pivoted side gage, a matrix backing bar, and a plurality of springs carried by the gage on which the bar is 65 mounted, said bar being arranged to position itself between the mold body and the edge of the matrix when the gage is swung to closed position. 70

6. In a casting box, the combination with the mold, of a pivoted side gage, and a spring-mounted matrix back carried by the gage and acting to engage the mold body behind the matrix and then engage the matrix 75 and clamp it against the side gage when the gage is swung to closed position.

7. In a casting box, the combination with the mold, of a side gage, a matrix having a bolster, a matrix-back movable with the gage 80 to matrix clamping position, and arranged to position itself between the matrix bolster and the mold as the gage moves to closing position and acting to hold the matrix bolster out of the plane of the matrix body. 85

In testimony whereof, I have hereunto set my hand in the presence of two subscribing witnesses.

AMANDUS H. CRUSE.
